(57) **CLAIM**

The ornamental design for a wagon, as shown and described.

DESCRIPTION

FIG. 1 is a perspective view of a wagon.

FIG. 2 is a front elevation view thereof. A rear elevation view is a mirror image of the front elevation view.

FIG. 3 is a right side elevation view thereof.

FIG. 4 is a left side elevation view thereof.

FIG. 5 is a top plan view thereof.

FIG. 6 is a bottom plan view thereof.

FIG. 7 is a cross-sectional view taken along the line 7-7 in FIG. 5, which omits the internal structure.

FIG. 8 is a cross-sectional view taken along the line 8-8 in FIG. 5, which omits the internal structure.

FIG. 9 is an enlarged cross-sectional view of the portion 9-9' in FIG. 8, which omits the internal structure; and,

FIG. 10 is a referential view with the cover opened.
